UNITED STATES PATENT OFFICE

SECONDO LUIGI CASELLA, OF NEW YORK, N. Y., ASSIGNOR TO BERNARD ULMANN CO.,
INC., OF NEW YORK, N. Y., A CORPORATION OF NEW YORK

SKEIN WINDING MACHINE

Application filed May 13, 1924. Serial No. 712,949.

This invention relates to machines for the automatic winding of embroidery thread of silk, cotton, yarn, or artificial silk, into skeins. Heretofore, it has been the common practice to wind the thread into skeins and to cut and tie the ends of the threads about the skein windings by hand; and while attempts have been made to devise machines for performing the winding and other operations mechanically and automatically, such machines have usually resorted to the tying of the severed ends of the thread which form the skein, in a manner somewhat similar to the hand operation. The automatic tying machines have not proven very successful and consequently practically all of the skein winding done at the present time is performed by hand labor. The principal object of this invention is to provide a machine for winding the thread in skeins, cutting the end of the thread after the skein has been finished, and securing the two ends of the skein, the operation of the machine being entirely automatic. Other more detailed objects of the invention will appear from the description hereinafter.

In the accompanying drawings, which illustrate an example of the invention without defining its limits, Fig. 1 is a front view of the machine; Fig. 2 is a side elevation; Fig. 3 is a section on the line 3—3 of Fig. 2; Fig. 4 is a section on the line 4—4 of Fig. 3; Fig. 5 is an enlarged front elevation of the upper front portion of the machine with the staple wire supporting reel and bracket removed; Fig. 6 is an enlarged side elevation of the upper front portion of the machine, a part thereof being shown in section; Figs. 7 and 8 are sections on the lines 7—7 and 8—8 of Fig. 6; Fig. 9 is an enlarged vertical sectional detail through the front head of the machine; Fig. 10 is an elevation of the front head as seen from the right hand side of Fig. 9; Fig. 11 is a detail plan view showing the skein supporting means with a number of skeins thereon; the parts shown in section illustrating the manner in which the skein threads are positioned preparatory to the stapling of the skeins and the cutting of the thread; Figs. 12 to 15 inclusive are enlarged

sectional details showing the various operating positions of the stapling mechanism; Fig. 16 is a section greatly enlarged, showing the lower portion of the stapling die and its cooperating parts; Fig. 17 is a section, greatly enlarged, of the manner in which the staple is clinched about the skein of thread and Fig. 18 is a view showing the completed skein. The machine consists of the following principal parts, which will be described under the following headings: A. The frame work and main driving mechanism; B. The skein supporting means; C. The skein winding means; D. Skein advancing means; E. Skein stapling means; F. Skein cutting and separating means, and G. Staple wire supporting and feeding means.

4. Frame work and main driving mechanism
(Figs. 1, 2 and 3)

The main frame of the machine consists of a casting of any suitable metal, having an extended base 10, from which the standard 11 projects upwardly; said standard having a laterally extending arm 12 projecting over and beyond the base 10. A motor 13, suitably secured as by the bolts 14 to the base 10 provides the motive power for operating the machine, and said motor is connected by means of a belt 15 with a pulley 16 forming a part of a tubular shaft 17. The tubular shaft 17 forms the outer member of a plurality of nested, concentrically arranged shafts, some of which are stationary to provide supports for the various parts of the machine to be hereinafter described, and the others of which are rotatable. The stationary members of this plurality of shafts consist of a central solid shaft 18 and a hollow shaft 19. The hollow shaft 19 which forms a support for the bearings of the rotatable shafts, is mounted in a suitable bore provided in the standard 11, and as shown in Fig. 3, is secured against movement within said bore by any suitable means such as the bolts 20. The solid shaft 18 is held against rotation by means of a strap 21, the ends of which are secured to the standard 11 by the cap screws 22, and the central part of said strap 21 is secured to the solid shaft 18 by the screws 100

55

23. Mounted in the annular space between the stationary hollow shaft 19 and the stationary shaft 18 is a rotatable hollow shaft 24; suitable bushings 25 and 26 being interposed between said shafts to furnish bearing surfaces for the shaft 24. Similar bushings 27 are interposed between the hollow stationary shaft 19 and the hollow rotatable outer shaft 17. The hollow shaft 17, adjacent to the pulley 16, is provided with a spur pinion 28 which meshes with a spur pinion 29 secured upon a shaft 30, shaft 30 passing through the standard 11 below the nested shafts, hereinbefore referred to, and parallel therewith. The rear end of the shaft 30 has secured thereto a bevel gear 31 meshing with a bevel gear 32 secured to the lower end of a vertically extending shaft 33, suitably mounted for rotation in the bearings 35 and 36, said shaft extending upwardly with its longitudinal axis intersecting the continuation of the axis of the nested shafts. A bevelled gear 37, secured on the vertically extending shaft 33, meshes with a bevelled gear 38, the gear 38 being connected to the hollow shaft 24. The upper end of the vertically extending shaft 33 has secured thereto a miter gear 39 which meshes with a similar gear 39a secured upon the rear end of a horizontally extending cam shaft 40.

B. Skein supporting means (Figs. 2, 3 and 11)

The outer end of the stationary hollow shaft 19 has secured thereto a spider 41 consisting of a pair of similar arms which extend laterally from a hollow boss 41a suitably keyed to said shaft 19, the outer ends of the spider arms terminating in bosses 42, each 40 having a central aperture in which a skein supporting rod 43 is rotatably mounted. Each rod 43 is of similar construction and is provided with an enlarged shoulder 44 which engages the front face of the boss 42; 45 the rear end of each rod 43 having secured thereto a collar 45, which cooperates with the shoulder 44 to prevent longitudinal movement of the rods within the aperture of said boss 42. As clearly shown in Figs. 2, 3 and 50 11 of the drawings, the forward end of the rod 43 projects outwardly beyond the boss 42 and said outer projecting end is screw threaded to form a thread of large pitch, as indicated at 46. The recessed portions of 55 the threads so formed form seats in which the threads of each skein are seated by the skein winding mechanism to be hereinafter described, and the spider 42 and rods 43 form in effect a skein supporting frame.

C. The skein winding means (Figs. 2, 3, 4 and 5)

Suitably secured upon the front end of the rotatable outer hollow shaft 17, to rotate therewith is an arm 47 having a pair of

laterally extending branches 48, 49 upon its outer end, which form with the arm 47 a substantially T-shaped member. The branch 48 is provided with an aperture 50 through which the thread 51 from the cone or bobbin 52 passes; said bobbin being frictionally secured upon a tapered shaft 53. The shaft 53 is non-rotatably secured upon a bracket 54, bolted to the hollow shaft 17 as by the bolts 55 (see Fig. 4), and said bracket is formed to provide a substantially cup-shaped member 56 which forms a guard within which the bobbin 52 is seated. A counter weight 57 is secured to the shaft 17 at a point diametrically opposite the shaft 53 for the purpose of balancing the weight of the bracket 54 and its associated parts. It will be noted from the foregoing description that the spider 41, being secured to the stationary hollow shaft 19, does not rotate, while the arm 47 which is secured to the hollow rotatable shaft 17 rotates about the spider 41 and its associated parts. The thread 51 which is passed through the aperture 50 of arm 48 is extended forwardly under a tension spring 58 suitably secured to the arm 47, after which the thread is passed through an aperture 59 to permit it to pass to the rods 43 in a manner which will be hereinafter more fully described. Shaft 18 is provided with a reduced extension 61 to which a yoke 60 is secured for catching the skeins after they have been wound, stapled and severed.

D. The skein advancing means (Figs 2, 3, 4 and 11)

Secured to the front end of the hollow shaft 24 is a large intermittent gear wheel or disc 62, the greater portion of the periphery of which, as shown in Fig. 5, is not provided with gear teeth. Two small sections of the gear wheel 62 are provided at diametrically opposite points with the gear teeth 63, which are adapted to engage with the small intermittent gear pinions 64, secured to the skein supporting rods 43. The gear pinions 64 are provided on the major part of their peripheries with gear teeth, as shown in Fig. 5, the gear teeth being omitted on the remaining portion thereof to engage with the smooth portion of the periphery of the gear wheel 62 in accordance with the usual construction of devices of this character; thereby to hold the rods 43 against rotation when the uncut portions of the cooperating gears 62 and 64 are in engagement. That section of the large intermittent gear wheel 62 which contains the gear teeth 63 is preferably made of a separate piece of material 65 which is dovetailed into the disc 62.

The machine illustrated is designed to form a skein of four windings and as the gear teeth 63 are operative after each half rotation of the disc 62, the driving means for the hollow shaft 17, the hollow shaft 24, and the

cam shaft 40, which shafts rotate the arm 47 and the disc 62 respectively, are so proportioned as to secure a speed of rotation of the arm 47 eight times as fast as the rotation of the disc 62 and four times as fast as the cam shaft 40; the speed of rotation of the parts of the machine in the example shown being 480 revolutions a minute for the arm 47 to 60 and 120 revolutions a minute for the disc 62 and cam shaft 40 respectively. It will thus be seen that for each half revolution of the disc 62, four revolutions of the arm 47 will occur and four loops of the thread will be laid within the innermost recesses or seats formed by the screw threads 46 for the reception of the threads. After the required number of loops of thread have been wound about the arms 43, the cooperating toothed portions of the gears 64 and 63 will come into engagement, thereby rotating the rods 43 in a direction to advance the skein of thread forwardly thereof.

E. Skein stapling means (Figs. 6, 7, 9 to 18 inclusive)

Bolted to the front end of the laterally extending frame arm 12 is a bracket or head 66, which head is provided with suitable guides for supporting and guiding the operating parts of the skein stapling devices. As shown more clearly in Fig. 9 the head 66 is provided with a bearing 67 in which the front end of the horizontally extending cam shaft 40, hereinbefore referred to, rotates. The rear portion of the head 66, as shown in Figs. 7 and 9, is provided with a pair of vertically extending guideways 68 in which a slide 69 reciprocates; said slide being retained within the guides 68 by a pair of plates 70 suitably secured, as by the screws 71, to the rear face of the head 66. The head 66 is also provided with a recess 72 intermediate the guideways 68 to provide a pocket for the reception of a spring 73. The lower end of the spring 73 is supported by a plate 74, suitably secured to the bottom of the head 66 and the upper end of said spring bears against a knee bracket 75 suitably secured to the slide 69, thereby normally urging said slide upwardly as will be readily understood. A roller 76 is secured to the rear face of the slide 69, as by the headed screw 77, said roller being held in engagement, by the action of spring 73, with the peripheral face of a cam 78, secured, as by the pin 79, to the cam shaft 40. The outer face of the slide 69 is provided with a central longitudinally extending recess or groove 69a in which the staple forming die 80 and the staple ejecting plunger 81 are received. The staple forming die 80, as more clearly shown in Figs. 12 to 16 inclusive, has a longitudinally extending aperture of rectangular cross section (see Fig. 7) in which the plunger 81 is slidably received. The die 80 is fixedly clamped within the lower

portion of the slide 69 by means of the plate 82, (Figs. 7 and 9), secured to the outer face of the slide 69 by the screws 83. Slidably mounted for reciprocation within the groove 69a of the slide 69 is secured a second slide 70 84, the lower reduced end 85 of which is provided with a vertically extending slot of rectangular cross section which forms a seat in which the upper end of the plunger 81 is retained; said plunger being clamped within 75 said seat by means of a plate 86 and screws 87 (Fig. 9). The upper end of the die 80 and the lower end of the second slide 84 are spaced apart from each other, as clearly shown in Fig. 9, and a spring 88, which is 80 coiled about the plunger 81, serves to urge the second slide 84 normally in an upper position, in contact with a bar 112. A cam roller 89, which is secured to the outer face 85 of the second slide 84, as by the headed screw 90, is adapted to be engaged by a cam 91 secured to the shaft 40, as by the pin 91a; the cams being constructed and arranged so as to cause a relative movement of the plunger 81 with respect to the die 80, at predetermined time intervals in a manner which will be hereinafter more fully described. The lower end of the head 66 is slotted out to provide a guideway for an anvil 92 which is slidably mounted within said guideway 95 and is retained in position therein by means of the plate 93. The outer end of the anvil 92 has secured thereto an upwardly projecting pin 94 (Figs. 9 and 12 to 16 inclusive), about which pin the stapling wire 95 is bent by the die 80 to form a yoke shaped staple 96 (Fig. 16). The rear end of the anvil 92 is machined at an angle to provide a cam face 97 with which a cooperating angular cam face, provided on the lower end of a flat 100 rod 98, is adapted to engage. The rod 98 is slidably mounted for vertical reciprocation within a guideway formed in the front face of the head 66, said rod 98 being retained within said guideway by the plate 99, secured as by the screws 100 to the head 66. The upper end of the rod 98 has secured thereto, as by the bolt 101, a cam roller 102, with the peripheral face of which, a cam 103 engages; the cam 103 being secured to the outer projecting end of the shaft 40 by means of the pin 104. A pair of springs 105, having their upper and lower ends respectively anchored to the transverse pin 106 and the studs 107, secured in the head 66 and rod 98 respectively, normally hold the rod 98 in its upper position with the face of the cam roller 102 in engagement with the peripheral face of the cam 103. The cams 103, 91, and 78, are so constructed and arranged that the inclined cam face of the rod 98 will engage with the inclined cam face 97 of the anvil 92, shortly before the slide 69 starts to descend. A spring 108 (see Fig. 6) having its front end anchored as at 108a and its rear end anchored to the 110

115

120

125

130

pin 109 secured in the anvil 92, serves to hold the anvil 92 normally retracted within its guideway. Immediately after the anvil 92 is moved forwardly by the engagement 5 of the cooperating cam faces of the anvil and rod 98, the throw of cam 78 begins to move the slide 69 downwardly, and causes the die 80 to begin its downward movement, the position of the parts at this time being as 10 shown in Fig. 12. It will be seen from Fig. 12, that, at this time, the plunger 81 is retracted within the lower end of the die 80 and that the pin 94, secured upon the front end of the anvil 92, is immediately beneath 15 the aperture of the die; both the aperture of the die and the pin 94 being in vertical alignment with and above the recess 110, formed in the die clinching anvil 111, seated within the projecting end 61 of the stationary 20 hollow shaft 18. The continued downward movement of the die 80 causes a piece of the stapling wire 95, which at this time has been moved forwardly into the path of the die by means to be hereinafter described, to be 25 severed by the cooperation of the rear wall of the die with a cutter 92a secured to an upwardly projecting lug 92b of the anvil 92. As the section of the wire 95 is cut in the manner just described, it is bent by the cooperation 30 of the die 80 and pin 94 into a yoke shaped staple 96 as clearly shown in Fig. 16, the position of the parts at this time being as indicated in Figs. 13 and 16. After the wire has been formed into a staple, the slide 35 69 moves upwardly, the die 80 carrying with it the partially formed staple. During the upward movement of the slide 69, the rod 98 also moves upwardly, thereby permitting the spring 108 to retract the anvil 92, the position 40 of the parts being as shown in Fig. 14.

The downward movement of the slide 69 just described is accomplished by the smaller throw 78a of the cam 78, (see Figs. 5 and 10), and after the parts have returned to 45 their upper position the throw 78b of the cam 78 again causes the slide 69 to be moved downwardly. Shortly after the engagement of the major throw 78b of the cam 78, the throw of the cam 91 engages the roller 89, 50 thus causing the plunger 81 to be moved outwardly of the die, the parts moving downwardly without relative movement, however, until the lower faces of the die 80 engage within the recess 110 of the anvil 111. After 55 the die engages within the recess of the anvil 111, the plunger 81 is moved downwardly of the die by the cam 91 to clinch the partially formed staple 96 about the threads which form the skein; the skein threads being held 60 in closely contacting engagement by the forks 201 to be hereinafter described, and the lower end of the die forming in effect a closed box in which the stapling operation is performed, as shown in Fig. 15. Secured upon each of the 65 side faces of the slide 69 is a plate 200, the

lower end of which is forked as at 201 (see Fig. 9), the lower arms of the forks flaring outwardly to engage readily over the threads forming the skein which is about to be stapled. It will be seen from Fig. 11 that the forked 70 ends 201 of the plates 200 straddle the reduced end 61 and cause the thread skeins to be held closely together for the stapling operation. An offset plate 202 is secured upon the left lower side face (Fig. 10) of the slide 75 69 over the plate 200 upon that side of the slide, and the lower end of the plate 202 is adapted to engage the outer side of the bunch of threads forming the skein about to be stapled, so as to insure the proper engagement of the forked ends of the plate 200 with the skein to be stapled. Immediately before the lower end of the plate 202 engages with the skein threads, the lower wedge-shaped end 203 of a rod 113a passes between the 80 threads forming the adjacent skeins to also assist in properly positioning the skein threads for the stapling operation. 85

F. Skein cutting and separating
(Figs. 10 and 11)

Secured to the upper end of the slide 69 is a horizontally extending bar 112 (see Figs. 9 and 10) which projects outwardly beyond the head 66 on both sides thereof. A rod 113 90 has its upper end reduced and threaded, which reduced threaded end passes through a suitable aperture provided in the rod 112 adjacent to one end thereof and a nut 114 is provided for clamping rod 113 securely to 100 the bar 112. Rod 113 extends downwardly and its lower end is supported by a bracket 115 secured to and projecting laterally from one side of the head 66. The rod 113a hereinbefore referred to is similarly secured to the 105 other end of bar 112 and is supported by a similar bracket 115a. A member 116 is secured to the extreme lower end of rod 113 and said member is provided with a laterally extending arm 117, to the outer end of which 110 is clamped, as by the plate 118, a small cutting knife 119. The lower end of the member 116 is provided with a small cylindrical rod which is tapered on its front and rear lower faces to form a separating wedge 120, 115 the purpose of which is to engage between adjacent skeins held by the rods 43 and separate the skeins preparatory to the cutting operation. Rod 113 has adjustably secured thereto, intermediate the rod 112 and bracket 115, a 120 bracket 121 which carries at its outer end a downwardly extending cylindrical rod 122, having its lower end pointed, as at 123 to assist the separating wedge 120 in separating the skeins. Secured to the side faces of the 125 reduced end 61 of the solid shaft 18 are the brackets 124 and 124a (see Figs. 10 and 11) the upper faces of the arms 125 and 125a of which extend parallel with the extension 61 and serve to support the skeins centrally of 129

the rods 43. The widened arm 125 of bracket 124 is provided with an aperture 126 through which the cutter 119 is adapted to pass; the upper face of said widened arm 125 forming a supporting surface for the connecting thread 127 between two adjacent skeins of thread as will be clearly seen in Fig. 11.

G. Staple wire supporting and feeding means (Figs. 1, 5, 6, 8 and 9)

Bolted to the planed face 130 of the bracket 66, is a reel supporting arm 131 having at the lower end thereof a boss 132. A pin 133, secured within said boss, serves as a supporting means for a circular disc 134, the outer face of the disc 134 being provided with an annular projecting flange or shoulder 135 about which the supply of stapling wire 95 is coiled. A retaining plate 136, having a central circular portion with a plurality of arms 137 radiating therefrom, is secured as by means of the knurled nut 138 upon the pin 133; the arms 137 being adapted to be seated in recesses 139 provided in the annular flange 135, and the construction and arrangement of the disc 134 and arms 137 being such as to hold the stapling wire 95 in properly coiled position upon the reel formed by these parts. The wire 95 is led from the reel to an inclined guide 140, secured within the lower slotted end of the head 66 (see Fig. 9) which serves to direct the wire 95 between a pair of feed rollers 141 and 142. The upper feed roller 141 is secured upon a shaft 143 which passes transversely across the lower end of the head 66 (see Fig. 8). The shaft 143 is rotatably mounted within a suitable bore provided in the head 66 and rotates about a fixed axis. The lower roller 142 is rotatably mounted in a pair of slideable bearings 145 mounted within suitable vertical slots provided in the lower end of the head 66. The lower end of the bearings 145 are bored out at 146 to provide a seat for the springs 147, which are coiled about the rods 148, and the plate 93 forms a support for the outer ends of the springs 147 thereby causing said springs to hold the roller 141 normally in engagement with the roller 142. The rods 148 project through suitable apertures provided in the plate 93, and are connected at their outer ends by a plate 149, for a purpose which will hereinafter appear. Gears 150, 151 are provided for driving the rollers 141 and 142 in unison and the following means are provided for actuating the rollers 141 and 142 intermittently. A ratchet gear 152 is secured upon the outer end of the shaft 143 and a mutilated gear 155 is rotatably mounted on said shaft adjacent to said ratchet gear. A spring pressed pawl 153 is pivotally mounted upon a pin 154 projecting outwardly from the face of the mutilated gear 155 and is adapted to engage with the ratchet gear 152 and move it in a counterclockwise direction

(Fig. 6). A rack 156, secured to pins 107, 157 extending transversely through the reciprocating rod 98, is provided with gear teeth which mesh with the teeth of the mutilated gear 155 and serve to impart the proper rotation to the feed rolls 141, 142.

For convenience in threading the stapling wire 95 through the machine, means are provided for moving the roller 142 out of engagement with roller 141 and such means comprises a small hand lever 160, fulcrumed to a bracket 161 which is secured to the plate 93. The lever 160 projects forwardly between the rods 148 and its lower face engages with the connecting bar 149, so that when the lever 160 is moved downwardly, it will press against the bar 149 and cause the rods 148 to pull the bearings 145, and shaft 144 downwardly and thereby move the peripheral face of the roller 142 out of engagement with the face of the roller 141. After the stapling wire 95 passes between the rollers 141, 142, it passes through a second guide 165, the guide 165 being suitably secured, as by the pins 166, within the lower slotted end of the head 66.

The operation of the stapling wire supporting and feeding means is as follows: the retaining plate 136 may be removed readily by unscrewing the knurled nut 138 thereby permitting a coil of stapling wire to be placed upon the annular flange 135, after which the retaining plate is placed back upon the pin 133 and secured in place by the knurled nut 138; the annular flange being of slightly greater thickness than the stapling wire to prevent any clamping of the wire coil by the retaining plate. The wire is preferably in the form of a thin flat ribbon of soft brass. The end of the wire is threaded through the guide 140, between the feed rollers 141 and 142 and then through the guide 165, the end of the wire being brought into alignment with the outer end of said guide 165.

When the rod 98 is moved downwardly by cam 103 to cause the anvil 92 to be moved outwardly, the rack 156 connected to said rod will rotate the mutilated gear 155 in a counterclockwise direction (Fig. 6) thus causing the pawl 153 to rotate the ratchet gear 152 and shaft 143 in the same direction. This will cause the feed rollers 141 and 142 to feed a length of the wire outwardly of the guide 165 just sufficient for the making of a staple 96, which length of wire is cut by the die 80 and cutter in the manner heretofore described. When the rod 98 and rack 156 move upwardly the construction of the ratchet gear 152 and pawl 153 is such that no rotation of the feed rollers occurs, as will be readily understood.

Operation

The operation of the machine is as follows, assuming that the stapling wire has 130

been placed upon the reel and properly threaded through the feed rollers and guides in the manner just described: A bobbin or cone of the thread to be skeined is placed upon the tapered shaft 53 and the end of the thread 51 is passed through the aperture 50 of the arm 48, under the tension spring 58 and through the aperture 59 of the rod 49. The operator makes one turn of the thread about the skein supporting rods 43 and holds the free end of the thread in her hand while she starts the machine in operation. The rotation of the motor 13 will obviously cause the outer hollow shaft 17 to be rotated rapidly, and as the arm 47 is secured to the hollow shaft 17, it will rotate about the disc 62. As has heretofore been pointed out the skein supporting rods 43 are stationary, and as the aperture 59 is in alignment with the inner seats formed by the threads 46 of the skein supporting rods, the thread will be formed in a plurality of winds or turns about the skein supporting rods. The machine illustrated in the drawings is designed to produce four turns of thread to a skein and during four complete revolutions of the arm 47 the machine performs a complete cycle of its movements. The position of the parts indicated in Fig. 5 indicates what might be termed the finishing position of the machine, and while the arm 47 has been performing its four revolutions, the other parts of the machine have been moving more slowly through their sequence of operations. During the first four revolutions of the arm 47 the uncut portions of the mutilated gears 62 and 64 are in engagement and the skein supporting rods 43 are held against rotation. Just as the fourth revolution of the arm 47 is completed, the teeth 63 of the gear 62 come to their operative position and cause the rods 43 to be rotated a complete revolution, thereby advancing the skein which has just been wound forwardly of the rods 43. During the first two revolutions of the arm 47, the throw 78a of the cam 78 comes into operation and causes the die 80 to be moved downwardly, the cam 103 as hereinbefore described causing the rod 98 to move downwardly and thereby move the anvil 92 out into the path of the die 80. The formation of the staple 96 by the die 80 and associated parts has been previously described. During the next two revolutions of the arm 47 the stapling operation is completed, and as shown in Fig. 11 of the drawing, the stapling operation is completed upon the skein next to the inner skein, as the arm 47 is winding the first turns of the next skein. Immediately before the stapling operation is completed, the cutting knife 119 which as heretofore described is connected with the slide 69, reaches its operative position, and as shown in Fig. 11, the cutting knife passes

between the two outermost skeins to sever the connecting thread 127. The stapling and cutting operations are completed practically simultaneously and immediately before the intermittent gears 63, 64, begin to operate. When the supporting rods 43 are rotated by the gears 63, 64, the outermost skein which has just been severed is carried by the screw threads 46 outwardly of the rod and drops upon the fork 60. It will be noted that the rotation of the skein supporting rods 43 in addition to advancing the skeins outwardly or longitudinally of said rods, also moves the skeins laterally of the rods or, considering the movement of the skeins with respect to the dimensions of the skeins, they are moved laterally by the screw threads 46 and longitudinally by their engagement with the periphery of said rods 43. Therefore the skeins are shifted sideways of the machine so that the staple which is placed upon each skein at the centre of the machine (see Fig. 11) is located to the left of the centre upon the outermost skein and the cutting mechanism is also located towards the left of the stapling mechanism. This sideways shifting of the skeins tends to keep the connecting thread 127 taut for the cutting operation.

While I have described the machine as one in which a skein of four turns or windings is made, it will be understood that any number of turns or windings might be used, by merely changing the gear ratios. Likewise the stapling wire could obviously be of any cross-sectional configuration, or of any suitable material.

It will be obvious that many changes, variations and modifications may be resorted to without departing from the spirit of my invention or the principles of construction described and illustrated herein. For example, it will be obvious that many changes in the construction and arrangement of the stapling wire supporting means may be resorted to or that any suitable stapling mechanism may be employed. Likewise any equivalent cutting or driving means may be substituted. Various changes may also be made in the thread winding device or the skein supporting and advancing means here- illustrated.

I claim:

1. The method which consists in continuously winding a thread to form successively a plurality of interconnected spaced skeins, intermittently and successively advancing the skeins so formed while maintaining them in spaced relationship, and, simultaneously with the winding of the skeins and during the dwell periods of the intermittent advance of the skeins, securing a fastening device about the turns of each successive skein, while serving the connecting thread between an adjacent pair of skeins after they have been secured by such fastening devices.

2. In a skein winding machine, a supporting framework, a plurality of shafts arranged in concentrically spaced nested relationship, mounted on said framework, a pair of said shafts being fixed against rotation and another pair being rotatable, driving means for rotating one of the rotatable shafts and gearing connecting it to the other rotatable shaft in continuously operative driving relationship, skein supporting means carried by one of the fixed shafts, thread winding means connected with one of said rotatable shafts and rotatable about said skein supporting means to form a plurality of skeins thereon, and means intermittently actuated by the other of said rotatable shafts to advance the skeins so formed out of the path of said thread winding means. 70
3. In a skein winding machine, a supporting frame having a plurality of skein supporting members rotatably mounted therein, said members being screw threaded to provide a plurality of spaced seats in which a plurality of skeins may be received, a stapling mechanism mounted between said members for securing a fastening device about the windings of the skeins, a cutter mounted adjacent to said stapling mechanism and to one side thereof and means to rotate said members to move the skeins both laterally and longitudinally into position to be operated upon successively by said stapling mechanism and cutter. 80
4. In a skein winding machine, a stationary supporting frame having a plurality of skein supporting members mounted for rotation therein, a thread winding device rotatable about said frame and members to wind successively a plurality of interconnected skeins on said members, a stapling mechanism for forming a length of wire into a staple and clinching it about the windings of said skeins, a cutter for severing said skeins and driving mechanism for rotating said thread winding device continuously, for causing an intermittent rotation of said skein supporting members, after a predetermined number of revolutions of said thread winding device, and for actuating said stapling mechanism and cutter during the operation of said thread winding device. 100
5. In a skein winding machine, a plurality of skein supporting members about which a plurality of open-looped skeins are formed, said members being provided with means to hold said skeins in spaced relationship with one another and to feed said skeins from said members, a stapling mechanism and a cutting device, each having a fixed part projecting into the path traversed by the central open part of the skein loops as they are fed from said members and cam means to intermittently actuate said stapling mechanism and cutting device. 115
6. In a skein winding machine, a frame- 120
- work, a supply of material adapted to be formed into staples mounted on said framework, a continuously rotating thread winding means to withdraw the thread from a thread supply and wind it into a plurality of spaced interconnected skeins, and a plurality of successively operated devices, actuated intermittently in timed relationship with said thread winding means, to withdraw a predetermined length of material from said supply of material, to cut said length and form it into a staple, to clinch said staple about the windings of a skein, to sever the thread connecting said secured skein from said thread supply, and to feed the secured skein from the machine; and means to cause a complete cycle of said successively operated devices to be performed during a predetermined number of revolutions of said thread winding means. 130
7. In a skein winding machine, a plurality of skein supporting members provided with recesses in which a plurality of interconnected spaced skeins are adapted to be wound, a thread winding device and means to rotate it continuously about said members to lay a thread and wind a skein in certain of said recesses, means for intermittently actuating said members after a predetermined number of revolutions of said thread winding device to move the wound skein out of the path of said winding device while a subsequent skein is being wound in spaced relationship to said wound skein, mechanism for securing a staple about a wound skein, a cutter for severing the connecting thread between the secured skein and said subsequent skein, and intermittently actuated means for operating said mechanism and cutter successively during the rotation of said thread winding device, to secure said staple about a wound skein and then to cut the connecting thread between said skein and the subsequent skein. 140
8. In a skein winding machine, a plurality of spaced supporting members provided with recesses in which a skein is adapted to be received, a continuously rotating thread winding device rotatable about said members to lay a thread and wind a skein in said recesses, and a member, for holding a supply of thread, rotatable with said device in fixed relationship thereto about said supporting members. 150
9. In a skein winding machine, a supporting framework, a thread supply, thread supporting means mounted on said framework and provided with a plurality of sets of spaced recesses, thread winding means rotatable about said thread supporting means to withdraw the thread from said thread supply and wind it into one of said sets of recesses to form a skein, intermittently actuated means operatively connected with said thread supporting means and operable after a predetermined number of revolutions of 160

- said thread winding means to advance the skein so formed from said one set of recesses into an adjacent set and thereby move the wound skein out of the path of said thread
- 5 winding means, a supply of stapling wire, a pair of staple forming members, including means to cut said stapling wire, means to feed a length of said wire into the path of said cutting means and means including one of said members to clinch the staple formed by said members about the skein of thread formed by said thread winding means.
- 10 10. In a skein winding machine, a pair of spaced horizontally extending skein supporting members provided with recesses in which a skein is adapted to be wound, a horizontally extending driving shaft located midway between said skein supporting members, a rotatable flyer arm secured to said shaft and
- 15 having thread engaging means adjacent to the outer end thereof, said thread engaging means travelling in a path located exteriorly of said skein supporting members to wind a thread in the recesses thereof, a support for holding
- 20 a supply of thread secured to said shaft approximately at right angles to said flyer arm to be rotatable with said arm, and a weight secured to said shaft to counterbalance said flyer arm and said support.
- 25 30 In testimony whereof I have hereunto set my hand.

SECONDO LUIGI CASELLA.
